PATENTED APR. 28, 1834.

8173X

E. WHITMAN.
ROASTING JACK.

(Apt. 28, 1834.)

315.

Ezra Whitman Jr.
Machine for turning meat and Coffee, while roasting
called Whitman's roasting Jack

The schedule referred to in these Letters Patent,
and making part of the same, containing a description in the words
of the said Ezra Whitman Junr himself, of his
Improvement in the machine for turning meat & coffee while roasting, called
Whitman's Roasting Jack—

To all persons to whom these Presents shall come,
Ezra Whitman Jr. of Winsthrop, County of Kennebec, State of
Maine sends greeting. Be it known that I the said Ezra Whitman
Jr. have invented, constructed & applied to use a new & useful
improvement in the machine for turning meat & coffee while roasting,
called, Whitman's roasting Jack, specified in the words following
to wit. Reference being had to the drawings Fig. 1. Plate 1. is
a toothed wheel on a horizontal shaft attached to this same shaft,
is the ratchet wheel 2. which has a click attached to the wheel 1.
as in similar wheels in clockwork. 3. is an arbor or small drum
over which passes a line attached to a weight as in clocks—

On the same shaft is another ratchet wheel 5. with its click
attached to it. The wheel No. 1. is revolved & drives the horizontal
pinion 6.—To this pinion is attached the upright or vertical shaft
No. 7.—

On the back side of the frame is another wheel which I call
a balance wheel having an escapement g at its centre, which plays
into the teeth of No. 1. The spit is perforated with holes, thro'
which may be thrust shorter horizontal spits armed sometimes with
hooks upon which may be hung such things as are required to be roasted,
or they may be run thro' and fastened to the upright spit, in that
manner a pair is also made thro' which the upright spit passes, &
may a like weight be suspended. This pair is represented at No. 11.

that however is not necessary, as a common pair may be set under in order to catch the gravy. (2)

I also attach more than one upright spit when necessary, as a common pair may be set under in order to catch the gravy of by extending a cross piece from the foot of the machine into which the foot of each upright spit may be inserted & to carry them; spur or cog wheels may be fastened at the tops of motion communicated from N.C. 7. to the others, a bright tin reflector may be attached to the post N.C. 12. which much facilitates the roasting. (2)

In order to roast coffee, a bevel pinion is fastened to the bottom of the upright spit, another bevel pinion is attached to the geareon of a common cylindrical coffee roaster which matches into each other, a socket is made in the bottom piece of the geareon of the coffee roaster is made with a bulge or projection in order to prevent its slipping out. This coffee roaster is shown attached in Plate 2.

In order to put this machine in motion after the meat is put upon the spit, the machine is wound up by means of the crank or by means of a red click put into a hole of the barrel or arbor N.C. 3. The weight there begins to descend and turns the shaft and the wheel $1\frac{1}{4}$ & consequently the spit 7. The balance wheel N.C. 8 with its escapement regulates the movement and causes it to move uniformly while the weight is standing. This regularity of movement may be affected by means of a pendulum and on the whole, the Pendulum is somewhat preferable.

Plate 2 represents the roaster with the pendulum; A. is the pendulum B the escapement C the ratchet wheel D a pinion E a large wheel matching to the pinion D. F the arbor or Barrel. G a bowl. H a pinion on the top of the spit & shaped P a pinion at the bottom of the spit connected with the pinion of the coffee roaster & with the weight.

Claims. - That I specifically claim as my invention and for

which I desire an exclusive right - is

1st The combination of machinery as above specified, to burn meat or coffee while roasting, &c. particularly 2nd The use of one or more upright spouts as above specified^{3rd}. The last addition is applied to the central shaft ^{4th} combination of the coffee-roaster as above specified.

In testimony that the above is a new and improvement, I have set my hand this 14. day of April 1834.
